DESIGN FOR AN ADAPTER FOR A SKI PACK SLED

Wallace E. Breuner, Oakland, Calif.

Application September 29, 1942, Serial No. 108,358

Term of patent 3½ years

To all whom it may concern:

Be it known that I, Wallace E. Breuner, an employee of the United States Government, a citizen of the United States, residing at Oakland, California, have invented a new, original, and ornamental Design for an Adapter for a Ski Pack Sled, of which the following is a specification, reference being had to the accompanying drawing, forming part thereof.

Fig. 1 is a perspective view of an adapter for a ski pack sled, showing my new design,

Fig. 2 is a side elevational view,
Fig. 3 is a side elevational view of the opposite side,

Fig. 4 is a bottom plan view, and
Fig. 5 is an end elevational view thereof.

I claim:

The ornamental design for an adapter for a ski pack sled, as shown.

WALLACE E. BREUNER.
